UNITED STATES PATENT OFFICE.

GEORGE A. BANNER, OF OMAHA, NEBRASKA, ASSIGNOR OF ONE-THIRD TO BIRT J. BATES AND ONE-THIRD TO CARL ANDERSEN, BOTH OF OMAHA, NEBRASKA.

PRINT PLATE.

Application filed June 2, 1927. Serial No 196,097.

This invention relates chiefly to cuts for printing and aims to simplify and facilitate the work of the engraver, whereby routing is obviated when preparing the type surface 5 for printing.

In accordance with the invention a plate is formed by two or more sheets of celluloid, or other suitable material adhesively united and of different color, the surface of the top 10 sheet being differently colored from the body of the sheet to enable the engraver to observe the work as the same progresses, since every line cut through the surface stands out in relief because of the difference in color of 15 the body of the sheet which appears through the surface cuts. Moreover, by making certain cuts of a depth to extend entirely through the top sheet, portions thereof may be separated from the bottom sheet to form 20 spaces, thereby obviating the accustomed step of routing to form appreciable spaces for high lights in printing.

While the drawing illustrates a preferred embodiment of the invention, it is to be 25 understood that in adapting the means to meet specific needs and requirements, the design may be varied and such other changes in the minor details of construction may be resorted to within the scope of the invention 30 as claimed, without departing from the spirit thereof.

For a full understanding of the invention and the merits thereof, reference is to be had 35 to the following description and the drawing, hereto attached, in which,—

Figure 1 is a top plan view of a printing block embodying the invention.

Figure 2 is a sectional view thereof on the line 2—2 of Figure 1.

Figure 3 is a view similar to Figure 2 of a modification.

Figure 4 is an enlarged detail sectional view, the dotted lines indicating a portion of the top sheet pried loose from the bottom 45 sheet, to provide space usually formed by routing.

The numeral 1 designates the block or other backing upon which the type plate is mounted. In forming the type plate in accordance 50 with this invention a plurality of sheets of suitable material are placed one upon the other and adhesively united by a suitable cement. The sheets may be of any thickness and usually consist of celluloid or analogous 55 composition. The top sheet is designated by

the numeral 2 and the bottom sheet by the numeral 3. It is preferred to have the top sheet 2 of a less thickness than the bottom sheet 3, thereby obviating the necessity of making a deep cut when it is required to remove a portion or portions of the top sheet to form spaces which ordinarily are provided by routing. The sheets 2 and 3 are of different colors, the bottom sheet 3 being dark and the top sheet light. It is preferred to have the top sheet 2 white and covered by a dark coat, which, when cut through, exposes the white body of the top sheet, thereby enabling the engraver to readily observe the work as it progresses, because of the white 60 line standing out in relief by contrast with the dark surface. When portions of the top sheet 2 are to be removed to provide spaces, the cuts are deepened to extend through the top sheet 2 so that the portion to be removed may be separated from the bottom sheet 3, as indicated by the dotted lines in Figure 4, whereby to form the space corresponding to the high light in printing. The numeral 4 designates the portion of the top sheet 2 adapted 65 to be removed, and this portion is completely separated from the remaining portion by a circumscribing cut, after which the portion to be removed may be pried from the bottom sheet 3 by means of a graver or the point of 70 a knife blade or other suitable implement.

The type plate, when prepared, may be mounted upon a block 1, platen or other support, according to the nature of the press employed. It is observed that the type plate 75 is flexible and may be readily applied to a curved platen or like surface to which it may be secured in any determinate way.

In the modification shown in Figure 3 a sheet of paper 5 is interposed between the sheets 2 and 3, and operates to facilitate the removal of the part or parts 4 of the top sheet when it becomes necessary to provide spaces 80 in the printing surface.

Having thus described the invention, I 85 claim:

1. A type plate comprising a plurality of sheets adhesively secured, the top sheet being adapted to receive the engraving and to have portions removed by being cut through to the 90 next sheet and separated therefrom.

2. A type plate comprising superposed sheets adhesively united, the bottom sheet being of a dark color and the top sheet being of a light color and covered with a dark coat- 95

ing, which, when cut through, exposes the engraving in light lines, and said top sheet adapted to have portions removed therefrom when cut through to the adhesive joint with 5 the next sheet.

3. A type plate comprising a plurality of superposed sheets adhesively united and of contrasting color, the bottom sheet being dark and the top sheet light and covered upon its 10 top side with a dark coating, through which the engraving is cut to expose the light material comprising the top sheet, and the latter having cuts extending therethrough and the

portion circumscribed removed to provide a space for the high light in printing. 15

4. A type plate comprising superposed sheets of celluloid, or analogous material, adhesively united with a sheet of paper therebetween, the bottom sheet being dark and the top sheet light, and covered by a dark coating through which the engraving extends and having a portion removed to provide the space for high light printing.

In testimony whereof I affix my signature.

GEORGE A. BANNER. [L.S.]
